ACETYLENE LAMP

Casimir V. Johanson, Cranford, N. J., and David B. Carse, Jr., New York, N. Y., assignors to The Oxweld Railroad Service Company, a corporation of Delaware

Application October 18, 1938, Serial No. 235,544

3 Claims. (Cl. 240—11.1)

This invention relates to self-contained acetylene lamps which may be exposed to weather conditions adversely affecting their operation.

Heretofore, considerable difficulty has been experienced in using enclosed-flame acetylene lamps in rainy weather, because of the tendency of rain to enter the burner housing and extinguish the illuminating flame. It has been found that rain tends to enter mainly through the ventilating chimney, and through the space between the lens-carrying bezel and the main section of the burner housing.

An object of this invention, therefore, is to provide a simple, durable, inexpensive, and yet efficient enclosed flame acetylene lamp provided with means for preventing the extinction of the illuminating flame by rain or other foreign matter entering from the outside.

Other objects of the invention include the provision of such a lamp having a burner housing provided with a ventilating chimney which is shielded externally against the entrance of water without impairment of the ventilating action; the provision of such a lamp having chimney shielding means adapted to drain the major part of the rain falling thereon beyond the edge of the burner housing; the provision of such a lamp having chimney shielding means which is mounted simply and sturdily in position; the provision of such a lamp having a main housing section and a lens-carrying bezel hinged thereto, in which a chimney shielding means is provided which does not interfere with the opening and closing of the bezel; and the provision of such a lamp having a main housing section and a lens-carrying bezel cooperable therewith, in which means are provided for preventing the entrance of rain between the main section and the bezel to the interior of the housing.

These and other objects of the invention will become apparent from the following description, considered in connection with the accompanying drawing, wherein:

Fig. 1 is a side elevational view, partly in section, of an acetylene lamp embodying the principles of the invention;

Fig. 2 is a perspective view of the chimney shielding hood; and

Fig. 3 is a sectional view taken along the line 3—3 of Fig. 1, looking in the direction of the arrows.

The invention is shown as embodied in a portable acetylene lamp of the type disclosed in U. S. Patents Nos. 1,822,625 and 1,855,395 issued on September 8, 1931, and April 26, 1932, respectively, in the names of William F. Hunt and Hermann C. Stelling. The invention may, however, be incorporated in other types of lamps.

Referring to Fig. 1 of the drawing, the invention is shown as applied to a portable acetylene

lamp comprising an acetylene generator G, a handle H in the form of a bail (shown in part), a housing R suitably secured to one side of the generator G and enclosing a source of light such as a vertical burner B and a reflector E behind the burner. The housing R also has a suitable light-emitting opening in the front thereof.

The housing R comprises a main open-fronted hollow parabolic section 1 closely fitting and secured to the rear of the reflector E. A ventilating chimney 2 is formed integral with and extends from the top of the housing R above the burner B. The chimney 2 has lateral venting means, such as vents 3, 3A, and 3B, in the side walls thereof, and a main vent 4 at the top end thereof. A bezel 5 carrying a lens 6 is hinged at the top to the front of the main section 1 by hinge 7, and is latched thereto at the side opposite such hinge, thus providing access to the interior of the housing. The bezel and lens assembly 5, 6 provides a closure, and when in the closed position, as shown in Fig. 1, the annular bezel shoulder 8 is aligned with the front annular edge or rim 9 of main section 1.

25 A protective hood 10 is rigidly secured over the top of the chimney 2 by bolts 11 threaded into bosses 12 formed integral with the inside wall of chimney 2. To insure the proper operation of 15 ventilating chimney 2, spacing sleeves 13 are positioned between the inner side of the top wall 14 of hood 10 and the top edge of chimney 2. Interposed in the joint between the annular bezel shoulder 8 and front rim 9 of main section 1 is an annular gasket 32 adapted to form a water 20 tight seal.

30 As shown in Fig. 2, the hood 10, in the present embodiment, comprises an unsymmetrical unitary metal member having the shape of a truncated quadrangular pyramid, open at the bottom and substantially closed on the top and sides, respectively, by an imperforate top wall 14 and side walls 15, 16, 17, and 18. It has been found 35 advantageous to construct the hood 10 with all side walls inclined downwardly and outwardly from the top wall 14, and with the rear corner edges 19 and 20 of substantially greater length than the front corner edges 21 and 22, so that the plane containing the lower ends of these corner edges is inclined at an angle to the top wall 14. In the present embodiment, the major part of the lower rim of the hood 10, comprising bottom edges 23, 24, and 25, also lies in this inclined plane. The major portion of the bottom edge 26 40 of the front wall 15 is in the form of an arc, which slopes downwardly on each side of the center of the bottom edge, meeting front corner edges 21 and 22 at the lower ends thereof. The front wall 15 is also provided with a centrally arranged substantially rectangular recess 27 extending upwardly from the bottom edge 26, and

the front wall 15 is bevelled for a short distance immediately above recess 27 as at 28. A centrally arranged curved recess 29 is also provided in the rear wall 17 and extends upwardly from the bottom edge 24. Bolt holes 30 are provided in top wall 14 to receive the bolts 11 and secure the hood to the chimney 2.

As embodied in the acetylene lamp of Fig. 1, the hood 10 is secured over the top of chimney 2 with each portion of the bottom edge of each side wall lying below the level of the vents in that wall of the chimney immediately adjacent thereto; and with the top wall 14 and all side walls spaced from chimney 2, as shown in Figs. 1 and 3, by means of spacing sleeves 13 through which pass bolts 11 threaded into bosses 12 internally of chimney 2. The whole bottom edge 26 of the front wall 15 lies over and close to housing R, and a portion of the wall 15 is located over and adjacent to the joint between main section 1 and bezel 5. Hood 10, furthermore, is positioned with the plane containing the lower ends of the corner edges 19, 20, 21, and 22 inclined downwardly away from the opening in the front of the main housing section 1 towards the rear of housing R, and with the lowest part of the lower rim of hood 10 extending well beyond the outer boundary of the housing R. Recess 27 and bevel 28 in the front wall 15 are positioned immediately above hinge 7 and are adapted to receive hinge 7 when bezel 5 is swung up to its open position. Recess 29 in rear wall 17 fits over one end of the handle H, and bottom edge 24 lies well beyond the rear boundary of housing R.

It may be seen, therefore, that the hood 10 very effectively shields the chimney 2 from the entrance of rain or other foreign matter through either the top or lateral vents in the chimney. Moreover, the inclined walls of the hood 10 so function as to carry most of the rain falling thereon to a point beyond the outer boundary of the housing R.

Thus, rain falling upon top wall 14 flows down side walls 15, 16, and 18 to the bottom edges thereof, all of which slope downwardly. Water, therefore, follows the downward slope of these bottom edges and is carried toward the rear of housing R and discharged beyond the rear boundary thereof from bottom edge 24 of rear wall 17. Water which flows down the wall 17, of course, also is discharged from bottom edge 24.

Although the foregoing description relates to means for preventing the ingress of rain or other foreign matter through chimney 2 to housing R, it is obvious that, in the acetylene lamp of Fig. 1, there exists another point subject to the entrance of rain, which may seriously affect the operation of the lamp. As has been mentioned before, bezel 5 is hingedly mounted upon main section 1 of housing R with the surfaces of annular shoulder 8 and front rim 9, of bezel 5 and main section 1, respectively, coinciding when bezel 5 is in the closed position. At the joint between coinciding surfaces 8 and 9, there exists a small space through which rain may have access to the interior of housing R. In order to prevent the entrance of rain, therefore, suitable sealing means is provided to seal the space between coinciding surfaces 8 and 9.

Shoulder surface 8 of bezel 5 is provided with

an annular groove 31 in which is set a gasket 32 of wicking or other suitable water-proof material. Groove 31 is so shaped as to receive only a portion of the thickness of gasket 32 and the remainder of gasket 32 forms an annular projection jutting from surface 8. When bezel 5 is latched in the closed position, the projecting portion of gasket 32 is compressed against the wide surface of front rim 9 of main section 1 and effectively seals the space between bezel 5 and main section 1 so that moisture is effectively excluded from housing R.

From the foregoing description, it may be seen that an acetylene lamp has been provided in which the burner housing is effectively protected against the entrance of rain or other foreign matter from the outside, with a resultant increase in the dependability of the lamp for operation in any kind of weather.

We claim:

1. In a lamp, the combination with an illuminating burner housing comprising a hollow main section having an opening, a closure for said opening, said closure having a hinge member on the top thereof connected to the top of said main section to permit swinging said closure to open and close the same, and a ventilating chimney associated with said main section, said chimney having venting means; of means for shielding said housing from the entrance of rain or the like, said means comprising a hood disposed over said chimney, and sealing means between said closure and said main section, the major portion of the lower rim of said hood being below the level of said venting means, a front portion of said lower rim being disposed above the joint between said closure and said main section, and the front of said hood having a recess therein adapted to receive said hinge member when said closure is in an open position.

2. In a lamp, the combination with an illuminating burner housing comprising a hollow main section having an opening, a closure for said opening, said closure having a hinge member on the top thereof connected to the top of said main section to permit swinging said closure to open and close the same, and a ventilating chimney associated with said main section, said chimney having vent means; of a hood disposed over said chimney, the major portion of the lower rim of said hood being below the level of said vent means, a front portion of said lower rim being disposed above the joint between said closure and said main section, and the front of said hood having a recess therein adapted to receive said hinge member when said closure is in open position.

3. A chimney hood for use with a lamp including an illuminating burner housing having a chimney associated therewith, said hood having the shape of a truncated polyangular pyramid, the lower ends of the corner edges and the major portion of the lower rim being in a plane angularly inclined to the top, two adjacent corner edges of said hood being of substantially equal length and shorter than the other corner edges, and the lower rim of said hood between said two substantially equal corner edges being inclined downwardly on each side of the center thereof.

CASIMIR V. JOHANSON.
